(57) **CLAIM**

The ornamental design for a tibial plateau leveling osteotomy plate, as shown and described.

DESCRIPTION

FIG. 1 is a top side view of a tibial plateau leveling osteotomy plate showing our new design;

FIG. 2 is a right left side view thereof;

FIG. 3 is a left side view thereof;

FIG. 4 is a bone facing side view thereof;

FIG. 5 is a perspective bone facing side view thereof; and, FIG. 6 is a perspective top side view thereof.

In the drawings, the broken lines are shown for the purpose of illustrating environment only and form no part of the claimed design.
